PROCESS FOR THE REDUCTION OF NITRONAPHTHENES

Thomas F. Doumani, Los Angeles, and Clarence S. Coe, Long Beach, Calif., assignors to Union Oil Company of California, Los Angeles, Calif., a corporation of California

Application March 14, 1944, Serial No. 526,421

13 Claims. (Cl. 260—566)

1

This invention relates to the preparation of derivatives of naphthalene hydrocarbons and applies particularly to preparation of oxygenated derivatives such as cyclohexanone oxime and cyclohexanone by a process involving initial nitration of the naphthalene, followed by reduction of the nitro-compound to the oxime, and hydrolysis of the oxime to the ketone. This is a continuation in part of copending application S. N. 512,796.

The chemistry of the naphthalene hydrocarbons is not well known, since they are not as reactive as the olefinic and aromatic hydrocarbons, and are not as readily available in pure form as are the paraffins. For these reasons, the more valuable derivatives of the naphthalene hydrocarbons have usually been prepared in the past by making the corresponding aromatic hydrocarbon derivative, and hydrogenating it. With the advent of improved methods of separation of naphthalenes from paraffins in petroleum fractions, however, pure naphthalenes are becoming more readily available, and it is the object of this invention to provide a method for producing valuable naphthalene derivatives directly from the parent naphthalene.

It has been found that the naphthenes, particularly cyclohexane, may be treated with nitric acid to obtain excellent yields of the mono-nitro substitution product (nitro-cyclohexane) and a single oxidation product, adipic acid.

single oxidation product, alpha-acid. It has now been discovered that further valuable derivatives may be obtained from the naphthenes. Particularly it has been found that the nitrocyclohexane prepared as above or in any other suitable manner, may be further treated by the reduction and hydrolysis processes described below to obtain cyclohexanone oxime, cyclohexanone, cyclohexanol, cyclohexylamine and other valuable derivatives, with hydroxylamine as a byproduct. The reactions may be diagrammed as follows:

2

(Reduction) ↓ (Reduction) ↓

5   6

N-Cyclohexyl hydroxylamine (II)   Cyclohexanol

10   11

(Reduction) ↓

10   12

Cyclohexylamine (III)   Dicyclohexylamine

15

20 Compounds I and II above may be considered as intermediates which may be formed in the reduction of nitrocyclohexane to cyclohexylamine. In the ordinary methods of carrying out
25 this reduction, there is no apparent formation of these compounds. In the reduction process of this invention, however, nitrocyclohexane is treated catalytically with hydrogen and simultaneously extracted with water to remove the
30 cyclohexanone oxime (I) and the substituted hydroxylamine (II) as formed, indicating that the above is the mechanism for the reaction. Since I and II may be hydrolyzed as indicated, to obtain cyclohexanone, cyclohexanol, and hydroxylamine, all of which are of considerable
35 value, the process appears to have commercial importance.

The reduction process of this invention may be carried out as indicated in the attached drawing. Referring to the drawing, the nitrocyclohexane or other nitronaphthene is introduced through line 1 into the upper part of tower 2 which is packed with a hydrogenation catalyst and operated hot and under pressure as described below. Water is introduced into the lower part of tower 2 through line 3, together with hydrogen from recycle line 4 and make-up line 5. The water and hydrogen pass up through the catalyst bed in tower 2 while in intimate contact with the down-flowing nitronaphthene, the latter preferably being the continuous phase. A portion of the nitronaphthene is reduced by contact with the hydrogen and the catalyst, and reduction products I and II above which are more soluble in water than are nitrocyclohexane or III, are

immediately extracted by the water. The excess hydrogen and the aqueous extract are separated from the nitronaphthene in the top section of tower 2 and flow out the top through line 6, and are separated from each other in vessel 7 while still hot, the hydrogen being recycled to tower 2 through lines 8, 4 and 3 and the aqueous solution being drawn off through line 9. The latter solution is then cooled in cooler 10 and discharged into vessel 11, in which the cyclohexanone oxime 10 crystallizes out and is separated by settling, filtration, or centrifuging, and is drawn off via line 12. Some of the mother liquor is withdrawn via line 13 and treated for further recovery of water-soluble products if desired and the remainder is 15 recirculated via lines 14 and 3 to reactor 2. The bottoms from reactor 2, consisting largely of unchanged nitrocyclohexane, with some of the less water-soluble products such as cyclohexylamine, are withdrawn via line 15, and recirculated to the 20 nitrocyclohexane feed line 1 via line 16. A portion of this recycle material is withdrawn through line 17, and purified of volatile reaction products such as the amine by distillation in column 18, the overhead being withdrawn through line 19, 25 and the bottoms being returned to line 16 via line 20. In this distillation, steam, admitted through line 21, may be used advantageously.

Pumps, valves, etc., are not shown in the drawing, but are to be inserted where required, as 30 it would be apparent to one skilled in the art. It is also apparent that vessel 7 may be a mere extension of the upper part of tower 2, operating at reactor pressure, or may operate at a lower pressure.

As catalysts for use in tower 2 in the above process, we may employ metals or compounds of metals of the first, second and third "transitional" groups, and particularly the metals of group VIII, preferably supported on a granular carrier to provide a large exposure of surface area. In the "transitional" groups it is meant to include those metals whose differentiating electron is in the second from the outermost shell. The first transitional group includes the elements having atomic numbers 21 to 30, i. e., scandium, titanium, vanadium, chromium, manganese, iron, cobalt, nickel, copper and zinc. The second transitional group includes the elements having atomic numbers between 39 and 48, i. e., yttrium, zirconium, columbium, molybdenum, masurium, ruthenium, rhodium, palladium, silver and cadmium. The third transitional group includes the elements having atomic numbers 57 and 72 to 80 inclusive, i. e., lanthanum, hafnium, tantalum, tungsten, rhentum, osmium, iridium, platinum, gold and mercury. These include the group VIII metals iron, cobalt, nickel, ruthenium, rhodium, palladium, osmium, iridium and platinum, of which nickel and platinum are preferred. The catalysts are preferably prepared by adsorbing on a granular carrier such as asbestos, carbon, clay, alumina, silica gel or the like, a solution of a soluble salt of the desired metal or metals, drying the impregnated solid and decomposing and reducing the salt to the free metal.

In tower 2 the temperature should be high, between about 100° and 350° C., with superatmospheric pressures sufficiently high to keep the water and nitronaphthene in the liquid state. Pressures up to about 100 atmospheres may be employed. The hydrogen should be present in substantial molal excess over the nitronaphthene, and may be diluted with inert gases such as nitrogen if desired. Flow rates should be controlled to

give contact times between about 1 minute and 1 hour or possibly more, depending on the temperature, catalyst activity, etc. In another mode of operation the nitronaphthene is introduced into tower 2 only at a rate sufficient to replace that which is reacted and removed by the water, thus allowing the water and hydrogen to bubble up through a relatively static nitronaphthene phase which is in contact with the catalyst. In another mode of operation the nitronaphthene may be introduced near the bottom of tower 2, together with the hydrogen or aqueous phase if desired, and allowed to separate from the aqueous phase and the hydrogen phase at the top of the tower above the catalyst bed, withdrawing the three phases separately and recirculating as desired.

As a specific example of the above operation, nitrocyclohexane may be introduced into line 1 at a rate of about 375 volumes per volume of catalyst per hour, with a recycle flow through line 16 of about 375 volumes per volume of catalyst per hour. Water (including both recycle water from line 14 and make-up water from line 3) may be introduced to tower 2 at a rate of about 750 volumes per volume of catalyst per hour, and enough hydrogen used to keep the pressure at 1000 lb. gage and to keep a reservoir of hydrogen in the top of vessel 7, with a reasonable flow up through tower 2. The contact time, estimated on the assumption of 50% voids in the catalyst, with 50% of the void space occupied by hydrogen gas, and 50% of the liquid being water, is about 1 minute for the above flow rates. The temperature in tower 2 may be about 150° C. The flow through the purification system, lines 17 and 20, and tower 18, need only be about 25 volumes (per volume catalyst) per hour, with an amine production of only about 4 volumes per hour, or 1% of the feed. The aqueous extract withdrawn from vessel 7 will be saturated with oxime (I) and contain small amounts of compound II. When depressured and cooled to about 80° F., the crystallized oxime may be recovered at a rate corresponding to a conversion of about 10%. If desired, the streams in lines 14 and 20 may be further purified by distillation of the nitrocyclohexane or removal of other reaction products before recirculation.

The catalyst employed in the above specific example was prepared by adsorbing an aqueous nickel nitrate solution on activated carbon and drying, igniting and reducing the product to obtain a catalyst containing about 5% metallic nickel. Employing the same catalyst in the conventional process of reduction, i. e., by subjecting nitrocyclohexane to a temperature of 150° C. in contact with the same catalyst and hydrogen at a pressure of 500 lb. gage, cyclohexylamine may be obtained, but no trace of the oxime (I) or compound II.

The cyclohexanone oxime (I) may be hydrolyzed to form cyclohexanone and hydroxylamine according to the equation shown above. The hydrolysis may be carried out by contacting the oxime with dilute aqueous mineral acids (hydrochloric, sulfuric, nitric, etc. of 0.1 N to 10 N concentration) at temperatures between about 0° C. and 150° C. For example, by adding 1 gram mol of the oxime (I) to 200 ml. of 5 N sulfuric acid, and heating at about 100° C. for 10 minutes, the oxime is converted quantitatively to the ketone and hydroxylamine sulfate. By merely chilling, the bulk of the ketone may be separated as an oily layer, and the hydroxylamine sulfate may

be crystallized out. Better separation may be obtained however, by distilling the product, whereby the ketone is distilled with some water, and the hydroxylamine salt remains in the rest of the water. By chilling the overhead and bottoms, the ketone and salt are recovered separately from the two fractions, as oil and crystalline solid, respectively.

The cyclohexanone formed as above may be reduced to cyclohexanol by known methods, or converted to other valuable derivatives. Cyclohexanol may also be prepared directly by hydrolysis of compound II separated from recycle stream 14, the hydrolysis being carried out under substantially the same conditions given above for hydrolysis of the oxime.

Although specific conditions of operation have been shown above, the invention is not to be limited thereby, for the process may be carried out under other conditions in the ranges indicated. Various combinations of the above processes may be used. For example, if a dilute mineral acid as described above is used instead of water, in line 3 and tower 2, the oxime (I) and compound II may be hydrolyzed as formed, and the extract withdrawn from vessel 7 through line 9 may contain little or no I or II, but instead, contain the hydrolysis products cyclohexanone, cyclohexanol, the hydroxylamine salt, and also the cyclohexylamine salt. This complicates the recovery problem somewhat, but suitable modifications of the methods described may be employed, as will be apparent to one skilled in the art.

The above description of the processes of this invention has been confined largely to the treatment of cyclohexane. It is to be understood, however, that other naphthalenes will respond to similar treatments and yield analogous products. Other unsubstituted naphthalenes such as cyclopentane and cycloheptane, will respond in substantially the same way as cyclohexane. When substituted naphthalenes are employed, larger

numbers of derivatives are obtained. For example, with methyl cyclohexane, the following types of nitronaphthalenes may be formed:

Primary   Secondary   Tertiary

The secondary nitronaphthene above will form derivatives analogous to the cyclohexane derivatives shown previously, except for the presence of the substituent group on the ring. Similarly, the primary nitronaphthene will form analogous derivatives, except for the presence of the nitro, oxime, hydroxy, ketone or other groups on the alkyl substituent group rather than on the ring.

15 The tertiary nitronaphthene will also form some of the corresponding derivatives, but it can not form the oxime. A nitroso derivative of the following type may be formed by the tertiary nitronaphthene:

30 It is apparent that where other substituted naphthenes such as dimethyl cyclopentane, ethyl cyclohexane, isopropyl cycloheptane, and the like, are employed, products corresponding to those shown above may be obtained.

35 It has been found that in the above oxidation process, small amounts of dinitrodicyclohexane are formed. This may be reduced by the novel hydrogenation process described above to obtain bicyclic derivatives corresponding to those made

40 from the secondary monocyclic nitronaphthalenes above.

For example:

The above compounds (except the hydroxyl-amine and the dinitrodicyclohexane) are all new compositions of matter, as are the corresponding derivatives prepared from the other unsubstituted and the substituted naphthenes as described above.

Modifications of the above processes which would reasonably occur to one skilled in the art are to be included in the scope of this invention as defined in the following claims.

We claim:

1. A process for the reduction of nitronaphthenes which comprises passing two streams, one of which is a gaseous stream comprising hydrogen and the other is water, through a body of liquid nitronaphthene which is at a temperature above about 100° C., at a pressure sufficient to maintain the water and the nitronaphthene in the liquid state and which is in contact with a hydrogenation catalyst, whereby the nitronaphthene is reduced to the corresponding oxime, and hydrolyzing said oxime with a dilute aqueous solution of a mineral acid to form the corresponding ketone.

2. A process according to claim 1 in which the reduction and hydrolysis are effected simultaneously by employing a dilute aqueous solution of mineral acid in place of water.

3. A process according to claim 1 in which the reduction and hydrolysis are effected simultaneously by employing a dilute aqueous solution of mineral acid in place of water and the ketone is extracted into the aqueous phase, removed from the reaction zone as formed and recovered from the aqueous phase.

4. A process according to claim 1 in which the reduction and hydrolysis are effected simultaneously by employing a dilute aqueous solution of mineral acid in place of water and in which the nitronaphthene is nitrocyclohexane and the ketone is cyclohexanone.

5. A process according to claim 1 in which the nitronaphthene is a secondary nitronaphthene.

6. A process according to claim 1 in which the nitronaphthene is nitrocyclohexane and the ketone is cyclohexanone.

7. A process according to claim 1 in which the hydrogenation catalyst comprises a metal selected from the first, second and third transitional groups.

8. A process for the reduction of nitronaph-

thenes which comprises passing two streams, one of which is a gaseous stream comprising hydrogen and the other is water, through a body of liquid nitronaphthene which is at a temperature above about 100° C. and at a pressure sufficient to maintain the water and the nitronaphthene in the liquid state and which is in contact with a hydrogenation catalyst, whereby the nitronaphthene is reduced to the corresponding oxime.

10. A process for the reduction of nitronaphthenes which comprises passing two streams, one of which is a gaseous stream comprising hydrogen and the other is water, through a body of liquid nitronaphthene which is at a temperature above about 100° C. and at a pressure sufficient to maintain the water and the nitronaphthene in the liquid state and which is in contact with a hydrogenation catalyst, whereby the nitronaphthene is reduced to the corresponding oxime and said oxime is extracted into the aqueous phase, removed from the reaction zone as formed and recovered from the aqueous phase.

11. A process according to claim 9 in which the nitronaphthene is nitrocyclohexane and the oxime is cyclohexanone oxime.

12. A process according to claim 9 in which the hydrogenation catalyst comprises a metal selected from the first, second and third transitional groups.

13. A process according to claim 9 in which the temperature of the nitronaphthene is maintained between about 100° C. and 350° C.
